(57) **CLAIM**

The ornamental design for nebulizer as shown and described.

DESCRIPTION

1. Nebulizer

1.1 : Perspective

1.2 : Front

1.3 : Back

1.4 : Left

1.5 : Right

1.6 : Top

1.7 : Bottom

1.8 : Perspective

FIG. 1.1 is a front, right side, top perspective view of a nebulizer showing the claimed design; FIG. 1.2 is a front elevational view thereof; FIG. 1.3 is a back elevational view thereof; FIG. 1.4 is a left side elevational view thereof; FIG. 1.5 is a right side elevational view thereof; FIG. 1.6 is a top plan view thereof; FIG. 1.7 is a bottom plan view thereof; and FIG. 1.8 is a back, left side, bottom perspective view

(Continued)

thereof; the dashed broken lines in the drawings depict portions of the nebulizer that form no part of the claimed design.

1 Claim, 8 Drawing Sheets
